UNITED STATES PATENT OFFICE.

HORACE W. ULRICH, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,296,023.

Specification of Letters Patent.

Patented Mar. 4, 1919.

Application filed July 12, 1917. Serial No. 180,133.

To all whom it may concern:

Be it known that I, HORACE W. ULRICH, a citizen of the United States, residing at East Orange, in the county of Essex and State of New Jersey, have invented certain new and useful Improvements in Telephone-Exchange Systems, of which the following is a full, clear, concise, and exact description.

10 This invention relates to telephone exchange systems, and has for its object the provision of a system in which the operators are prevented from listening in on established connections between telephone lines.

15 In accordance with this invention each connecting circuit for joining together telephone lines is provided with means whereby when a listening key thereof is actuated an operator's telephone set is connected to one 20 end of the connecting circuit and a relay is simultaneously energized to sever the continuity of the connecting circuit. The listening keys of the connecting circuits are 25 also provided with contacts and circuit connections by means of which, when two keys of different connecting circuits are simultaneously actuated, an energizing circuit for a common relay is established, thereby preventing 30 the connection of the operator's telephone set to either of the connecting circuits with which the actuated listening keys are associated.

35 A more complete understanding of this invention may be had from the following description, considered in connection with the accompanying drawing illustrating one embodiment thereof.

40 In the drawing there is shown a telephone line A extending from a subscriber's station to a central office and there suitably joined with a circuit C, shown between the lines 1-1 and 2-2. This circuit C is suitably connected in any desired manner with a circuit 45 extending to a private branch exchange and there joined with a connecting circuit D, shown between the lines 3-3 and 4-4. The other end of the connecting circuit D is suitably joined with a telephone line B, extending 50 from the private branch exchange to a station local thereto. Two listening keys 5 and 6 are associated with the connecting circuit D. These listening keys may be controlled by a common plunger (not 55 shown) which, when moved in one direction,

opens the normally closed contacts and closes the normally opened contacts of one listening key, and, when moved in the opposite direction, opens the normal and closes the alternate contacts of the other key. Between the lines 7-7 and 8-8 there are shown portions of two listening keys 15 and 16 associated with a connecting circuit similar to D, and to the left of line 8-8 there are shown portions of two listening keys 25 and 26 associated with a third connecting circuit, similar to D. The listening keys of each of the connecting circuits are exactly alike, but for convenience, only the listening keys of connecting circuit D are shown 70 in full. A relay 9, common to the connecting circuits at the private branch exchange, has normally closed contacts in circuit with an operator's telephone set. It will be understood, of course, that a plurality of lines 75 similar to line B terminate at the private branch exchange and that a plurality of lines similar to line A may be extended to the private branch exchange. Furthermore, that the connecting circuits at the private 80 branch exchange may be employed to interconnect lines local thereto, as well as a line local thereto and a line extended thereto over suitable circuits.

Assuming that subscribers A and B are in 85 communication and that the operator desires to communicate with subscriber B, the listening key 6 is actuated. The actuation of this listening key causes the operation of relay 10, individual to the connecting circuit 90 D, over a circuit from battery through the winding of relay 10, conductor 11 and contact 12 of listening key 6 to ground. The operation of relay 10 opens its normally closed contacts, thereby interrupting the 95 continuity of the connecting circuit D and connecting a source of current 13 to the right-hand end of the connecting circuit D through retardation coils 14 and the alternate contact of relay 10. This battery is 100 connected to this end of the cord circuit to furnish current for operating the transmitters of the operator's telephone set and the local set B. The actuation of listening key 6 also connects the operator's telephone set 105 to the right-hand end of the connecting circuit D through the normally closed contacts of relay 9, conductors 17 and 18, contacts 19 and 20 of the listening key 6 and conductors 21 and 22.

Should the operator desire to communicate with subscriber A instead of B, listening key 5 instead of 6 is then actuated, thereby energizing relay 10 over a circuit 5 from battery through the winding of this relay, conductors 11 and 23 and contact 24 of listening key 5 to ground. The energization of relay 10 opens its normally closed contacts to interrupt the continuity of the 10 connecting circuit, as hereinbefore described. The operator's telephone set is now connected with the left-hand end of the connecting circuit D, through the normally closed contacts of relay 9, conductors 17 and 18, conductors 27 and 28, contacts 29 and 30 of 15 listening key 5 and conductors 31 and 32. Should the connecting circuit with which listening keys 15 and 16 are associated be connected with a telephone line at the same 20 time that the connecting circuit D is joined to telephone line B, and should the operator attempt to connect these two lines together by actuating a listening key of each of these connecting circuits, and thereby attempt to 25 listen to the conversation, relay 9 will be energized to prevent the connection of the operator's telephone set to either of the connecting circuits. For example, assuming that the listening keys 6 and 16 are actuated, 30 the relay 9 will then be operated over a circuit from battery through the winding of relay 9, contact 35 of listening key 6, common conductor 36 (which is multiplied to normally open contacts of each of the listening keys), contact 37 of listening key 16, portion 38 of a common circuit lead extending in series through normally closed contacts of all the listening keys, contact 39 of listening key 5, portion 40 of the common series circuit lead and contact 41 of 35 listening key 6 to ground.

From the above description, it will be evident that an operator is prevented from listening in on a conversation between two 40 telephone lines joined together by a single connecting circuit and that it is also impossible for the operator to connect two lines together through portions of two connecting circuits and the operator's telephone set. 45 By the provision of a common circuit lead multiplied to normally open contacts of the several listening keys and a common circuit lead extending in series through normally closed contacts of the several listening keys, 50 the common relay 9 will be energized when any two listening keys of different connecting circuits are simultaneously actuated.

What is claimed is:

1. A telephone exchange system comprising two telephone lines, a connecting circuit joining the telephone lines together, an operator controlled switch, a relay energized upon the actuation of the switch to interrupt the connecting circuit, and an operator's telephone set connected with one end 55 of the connecting circuit by the actuation of the switch.

2. A telephone exchange system comprising two telephone lines, a connecting circuit joining the telephone lines together, a source 70 of current, an operator controlled switch, a relay energized upon the actuation of the switch to interrupt the connecting circuit and to connect the source of current to one end thereof, and an operator's telephone set 75 connected, by the actuation of the switch, with the end of the connecting circuit to which the source of current is connected.

3. A telephone exchange system comprising telephone lines, connecting circuits for interconnecting the lines, an operator's telephone set, a listening key for each connecting circuit actuated to connect the operator's telephone set thereto, a relay common to the connecting circuits adapted when energized 80 to prevent the connection of the operator's telephone set to the connecting circuits, and an energizing circuit for the relay established upon the simultaneous actuation of two keys and including contacts of both 85 keys connected in series.

4. A telephone exchange system comprising telephone lines, connecting circuits for interconnecting the lines, a listening key for each connecting circuit actuated to connect the operator's telephone set thereto, a relay common to the connecting circuits adapted when energized to prevent the connection of the operator's telephone set to the connecting circuits, a circuit lead common to and connected to normally open contacts of the listening keys, a circuit lead common to and including normally closed contacts of the listening keys, and an energizing circuit for the relay established by the simultaneous 90 actuation of two keys and including portions of both circuit leads and contacts of both actuated keys.

5. A telephone exchange system comprising telephone lines, connecting circuits for interconnecting the lines, a listening key for each connecting circuit actuated to connect the operator's telephone set thereto, a relay common to the connecting circuits adapted when energized to prevent the connection of the operator's telephone set to the connecting circuits, a circuit lead common to and multiplied to normally open contacts of the listening keys, a circuit lead having contacts of the listening keys included in series there-in and in series with one another, and an energizing circuit for the relay established by the simultaneous actuation of two keys and including portions of both circuit leads and contacts of both actuated keys.

6. A telephone exchange system comprising telephone lines, connecting circuits for interconnecting the lines, an operator's telephone set, a listening key for each connecting circuit adapted when actuated to con- 120 125 130

nect the operator's telephone set thereto, an electromagnetic relay common to the connecting circuits adapted when energized to prevent the connection of the operator's telephone set to the connecting circuits, and an energizing circuit for the relay established upon the simultaneous actuation of the two

keys and including the winding of the relay and a contact of one and two contacts of the other key, the contacts being connected in series.

In witness whereof, I hereunto subscribe my name this 10th day of July, A. D. 1917.

HORACE W. ULRICH.
